UNITED STATES PATENT OFFICE.

ULRICH FISCHER AND JOHN HUESLER, OF ST. LOUIS, MISSOURI.

DESIGN FOR A SALT-SHAKER.

41,924.

Specification for Design. Patented Nov. 14, 1911.

Application filed September 29, 1910. Serial No. 584,583. Term of patent 7 years.

To all whom it may concern:

Be it known that we, ULRICH FISCHER and JOHN HUESLER, citizens of the United States, and residents of St. Louis city, in the State of Missouri, have invented a new, original, and ornamental Design for a Salt-Shaker, of which the following is a specification, reference being had to the accompanying drawing, forming part thereof.

The figure is a perspective view of a salt shaker, showing our new design.

We claim:

The ornamental design for a salt shaker, as shown.

ULRICH FISCHER.
JOHN HUESLER.

Witnesses:

ALBERT H. PARKINSON,
LEE KAMMERER.
